UNITED STATES PATENT OFFICE

JAMES E. PATTON, JR., OF MILWAUKEE, WISCONSIN.

DESIGN FOR A COLOR-EXHIBITING CARD.

SPECIFICATION forming part of Design No. 31,910, dated November 28, 1899.

Application filed November 8, 1899. Serial No. 738,056. Term of patent 14 years.

To all whom it may concern:

Be it known that I, JAMES E. PATTON, Jr., a citizen of the United States, residing at Milwaukee, in the county of Milwaukee and State 5 of Wisconsin, have invented and produced a new and original Design for a Color-Exhibiting Card; and I do hereby declare the following to be a full, clear, and exact description of the same, reference being had to the accompanying drawing, forming a part thereof.

The drawing represents a view of a color-exhibiting card embodying my new design.

My design relates to the new and original shape or configuration of the article.

15 The leading or essential feature consists in the unitary design for a color-exhibiting card made the subject of illustration, comprising the shape of the top and bottom, formed on straight horizontal lines, the shape of one side following a vertical line for the greater

part of its height and thence continued in an outwardly-extending straight oblique line, meeting the horizontal top line, and the shape of the opposite side following a continuous curved line composed of series of alternate 25 irregular convex and concave lines.

A minor feature of said design is the short horizontal line connecting the vertical and oblique lines on one side.

Having thus described my invention, what 30 I claim as new, and desire to secure by Letters Patent, is—

The design for a color-exhibiting card, substantially as herein shown and described.

In testimony whereof I affix my signature 35 in presence of two witnesses.

JAMES E. PATTON, JR.
